INFANT'S FOLDING BATH STAND

Charles T. De Puy, Brighton, N. Y., assignor to
Trimble Nurseryland Furniture, Inc., Roches-
ter, N. Y., a corporation of New York

Application March 4, 1948, Serial No. 13,061

7 Claims. (Cl. 4—177)

1

This invention relates to an infant's folding bath stand of the general type comprising two pivotally connected leg frames between which a collapsible tub is supported, and it has for its purpose to afford such a folding structure in which each leg frame is formed from an integral metal tube bent to provide top and bottom rails and vertical connecting portions.

More particularly, the invention has for its purpose to afford a cross-legged folding construction in which each leg frame consisting of a cylindrical metal tube has rounded corners formed by bending the tube to provide a one-piece frame.

With such a tubular metal leg frame structure having rounded corners, the length of tub that can be supported between the top rails of the leg frames is determined by the straight portions of the top rails, and it is a further object of the invention to so construct the inner or front leg frame at its upper portion that a tub of maximum length can be supported between the leg frames, limited only by the length of the straight portion of the top rail of the rear or outer leg frame.

A further purpose of the invention is to afford a construction that can be economically manufactured from cylindrical tubular metal stock and readily assembled to afford a practical and efficient structure, in which each leg frame formed of a single metal tube bent to the desired form has separable telescoping end portions extending through the tub and maintained in supporting relation thereto by frictional engagement with each other and by the spring action of the leg frame.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in front elevation of an infant's folding bath stand constructed in accordance with a preferred embodiment of the invention;

Fig. 2 is a view in end elevation of the same;

Fig. 3 is a plan view, with parts broken away;

Fig. 4 is a detail view, partially broken away, showing a top corner of the inner or front leg frame, and the telescoping end portions thereof;

Fig. 5 is a similar view of the rear or outer leg frame, and

Fig. 6 is an enlarged detail elevation, partially

in section, showing the telescoping relation between the separable end portions of the inner leg frame.

Referring more particularly to the drawings in which like reference numerals refer to the same parts throughout the several views, the invention is illustrated in connection with an infant's folding bath stand including pivotally connected leg frames, each of which is formed of an integral cylindrical metal tube bent to the required form.

In the construction shown, the invention comprises an inner or front leg frame designated generally at 1 and arranged within the outer or rear leg frame 2, the vertical portions of the leg frames being pivotally connected by suitable means such as bolts 3. The leg frames include vertical portions terminating in rounded corners 4 at their lower ends which form part of the bottom rail and merge into the upwardly inclined portions 5 connecting with the elevated central horizontal portions 6 which permit placing one's foot under the elevated portion of the bottom rail while the vertical portions terminate at their upper ends in top rails comprising elongated portions 7 telescoping within the short connecting portions 8, the portions 7 and 8 of the top rails being connected with the vertical portions by rounded corners 9 as shown.

Since both leg frames are rounded at the ends of their top rails or their upper corners and the inner leg frame is pivoted within the outer leg frame, the straight portion of the top rail of the inner leg frame would necessarily be of somewhat less length than the straight portion of the rear leg frame and thus limit the length of tub that can be supported between them if both leg frames are similarly formed, and in order to enable constructing both leg frames of cylindrical metal tubes and bending them to afford rounded corner connecting portions and at the same time support a tub therebetween of the maximum length that can be accommodated by the outer or rear leg frame, the vertical portions of the inner or front leg frame are provided at their upper ends with outwardly flaring curved portions 12 that extend to a point in vertical alignment with the vertical portion of the outer leg frame, such outwardly flaring portions 12 forming continuous curves with the rounded corners and merging into the vertical top rail comprising the elongated and short connecting portions already described which when connected together form a continuous leg frame that is extremely rigid and firm, giving substantial support to the tub.

With this arrangement of outwardly flaring portions 12, the straight portion of the top rail of the inner leg frame affords the same length for supporting the tub as the top rail of the outer leg frame, which is supported outside the inner leg frame and therefore of greater length measured between its vertical portions at the pivotal point, and thus a tub of maximum length can be supported between the top rails of the leg frames, or of a length as great as the outer leg frame will accommodate.

The tub which is of rubberized fabric or other suitable flexible material is indicated at 13, and constructed with suitable tubular portions or casings 14 along its front and rear edges within which are received the top rails of the leg frames, which thus support the tub while the latter limits the spreading or opening movement of the leg frames when they are unfolded.

The elongated portions of the top rails indicated at 7 are provided with tapered portions 15 terminating in cylindrical end portions 16 of reduced diameter, which enter the adjacent ends of the short connecting portions 8 and act as guiding means in positioning the elongated portions within the short connecting portions, while the tapered portions 15 exert a wedging action on the surrounding surface of the edge of the short portions of the tube.

Each leg frame comprises a cylindrical metal tube as illustrated in Fig. 1, with its top rail comprising the elongated and short connecting portions which are separable to permit assembling the flexible tub on the leg frames, each integral metal tube being sufficiently resilient and yieldable to permit the ends to be swung apart while assembling the tub thereon.

To assemble the tub on the leg frames, the elongated portions 7 of the two leg frames are separated from the short connecting portions 8, the spring action of the frames permitting such separation, and the elongated portions are then threaded through the tubular sections or casings of the tub, which is then pushed entirely on to the elongated portions 7 of the top rails sufficiently to permit inserting the extremities of the elongated portions into the openings at the ends of the short connecting portions, as shown in Figs. 4, 5 and 6.

The spring action and resilience of each metal leg frame and the frictional engagement of the tapered portion 15 act to hold the separable parts of the top rail together and the tub is then pulled over the short connecting portions of the top rails as shown in Figs. 1 and 3, the leg frames being held in pivotal relation by means of the bolts or other attaching devices 3, and the integral connections between the vertical portions of the leg frames through the bottom rails afford sufficient stiffness and rigidity to the leg frames so that the separable portions of the top rails are held together in proper retaining relationship to the tub, and the latter cannot be displaced from the leg frames except by forcibly separating the telescoping portions of each leg frame.

The integral connecting portions at the bottoms of the leg frames afford stiffness and rigidity to the stand as a whole, and by providing the bottom rails with the upwardly inclined portions 5 and the elevated horizontal portions at the center, which are thus raised above the floor, there is nothing to interfere with the positioning of a person's foot under the stand when bathing or dressing an infant, and there is consequently nothing on the floor to obstruct the natural posi-

tion of the feet under the stand or otherwise to interfere with its normal and proper operation.

While the invention has been described with reference to the particular construction shown, it is not confined to the details illustrated herein, and this application is intended to cover such modifications or departures as may come within the purposes of the improvement or the scope of the following claims.

10. I claim:

1. An infant's folding bath stand consisting of pivotally connected leg frames, each of which comprises an integral cylindrical metal tube including vertical portions, a bottom rail, a top rail consisting of separable elongated and short telescoping portions, said telescoping portions including a cylindrical terminal portion of reduced diameter and an adjacent tapered portion at one end of the tube fitting within the other end of the tube and wedging against the inner edge thereof, said telescopic joint being at one end of the top rail, rounded corners connecting the vertical portions with the top and bottom rails respectively, and a collapsible tub secured at its front and rear edges to said top rails.

2. An infant's folding bath stand consisting of pivotally connected leg frames, each of which comprises an integral cylindrical metal tube including vertical portions, a bottom rail, a top rail consisting of separable elongated and short telescoping portions, rounded corners connecting the vertical portions with the top and bottom rails respectively, each bottom rail including an elevated central portion permitting stepping thereunder and inclined portions connecting said central portion with the adjacent lower rounded corners, and a collapsible tub secured at its front and rear edges to said top rails.

3. An infant's folding bath stand consisting of pivotally connected leg frames, each of which comprises an integral cylindrical metal tube including vertical portions, a bottom rail, a top rail consisting of separable elongated and short telescoping portions, said telescoping portions including a cylindrical terminal portion of reduced diameter and an adjacent tapered portion on one end of the tube fitting within the other end of the tube and wedging against the inner edge thereof, said telescopic joint being at one end of the top rail, rounded corners connecting the vertical portions with the top and bottom rails respectively, each bottom rail including an elevated central portion permitting stepping thereunder and inclined portions connecting said central portion with the adjacent lower rounded corners, and a collapsible tub secured at its front and rear edges to said top rails.

4. An infant's folding bath stand consisting of pivotally connected inner and outer leg frames, each of which comprises an integral cylindrical metal tube including vertical portions, a bottom rail, a top rail consisting of separable elongated and short telescoping portions, the vertical portions of the inner leg frame terminating at their upper ends in outwardly flaring curved portions extending to points flush with planes containing the vertical portions of the outer leg frames whereby the straight portions of the top rails of both leg frames are of the same length to accommodate a tub as long as the outer leg frame will permit, rounded corners connecting the top rail of the inner leg frame with said outwardly flaring curved portions and the top rail of the outer leg frame with the vertical portions thereof, rounded corners connecting the bottom rails with said

vertical portions, and a collapsible tub connected at its front and rear edges to said top rails.

5. An infant's folding bath stand consisting of pivotally connected inner and outer leg frames, each of which comprises an integral cylindrical metal tube including vertical portions, a bottom rail, a top rail consisting of separable elongated and short telescoping portions, the vertical portions of the inner leg frame terminating at their upper ends in outwardly flaring curved portions extending to points flush with planes containing the vertical portions of the outer leg frame whereby the straight portions of the top rails of both leg frames are of the same length to accommodate a tub as long as the outer leg frame will permit, rounded corners connecting the top rail of the inner leg frame with said outwardly flaring curved portions and the top rail of the outer leg frame with the vertical portions thereof, rounded corners connecting the bottom rails with said vertical portions, and a collapsible tub connected at its front and rear edges to said top rails, said telescoping portions including a cylindrical terminal portion of reduced diameter and an adjacent tapered portion at one end of the tube fitting within the other end of the tube and wedging against the inner edge thereof and said telescopic joint being at one end of the top rail.

6. An infant's folding bath stand consisting of pivotally connected inner and outer leg frames, each of which comprises an integral cylindrical metal tube including vertical portions, a bottom rail, a top rail consisting of separable elongated and short telescoping portions, the vertical portions of the inner leg frame terminating at their upper ends in outwardly flaring curved portions extending to points flush with planes containing the vertical portions of the outer leg frames whereby the straight portions of the top rails of both leg frames are of the same length to accommodate a tub as long as the outer leg frame will permit, rounded corners connecting the top rail of the inner leg frame with said outwardly flaring curved portions and the top rail of the outer leg frame with the vertical portions thereof, rounded corners connecting the bottom rails with said vertical portions, each bottom rail including an

elevated central portion permitting stepping thereunder and inclined portions connecting said central portion with the rounded corners, and a collapsible tub secured at its front and rear edges to said top rails.

7. An infant's folding bath stand consisting of pivotally connected inner and outer leg frames, each of which comprises an integral cylindrical metal tube including vertical portions, a bottom rail, a top rail consisting of separable elongated and short telescoping portions, the vertical portions of the inner leg frame terminating at their upper ends in outwardly flaring curved portions extending to points flush with planes containing the vertical portions of the outer leg frame whereby the straight portions of the top rails of both leg frames are of the same length to accommodate a tub as long as the outer leg frame will permit, rounded corners connecting the top rail of the inner leg frame with said outwardly flaring curved portions and the top rail of the outer leg frame with the vertical portions thereof, rounded corners connecting the bottom rails with said vertical portions, each bottom rail comprising an elevated central portion permitting stepping thereunder and inclined portions connecting said central portion with the rounded corners, and a collapsible tub secured at its front and rear edges to said top rails, said telescoping portions including a cylindrical terminal portion of reduced diameter and an adjacent tapered portion on one end of the tube fitting within the other end of the tube and wedging against the inner edge thereof, said telescopic joint being at one end of the top rail.
